[57] ABSTRACT

A machine for producing zigzag folds in continuous business forms or like strip material. The strip material moves over a horizontal feed roller and then downward between a pair of opposed endless belt units to an underlying support surface. A hold-down roller is biased to engage the feed roller, with the material sandwiched therebetween, immediately above the point at which the material discharges from the feed roller. The material, upon engagement with the support surface, loops alternately in opposite directions beneath the belt units and between spaced stops, one of which is rounded so as to allow for a smooth continuous movement of the folded material therebeyond. Material boosting means periodically engage the looped material immediately prior to engagement with the stops so as to insure a proper movement thereagainst.

SHEET 3 OF 3

FOLDER FOR BUSINESS FORMS

The invention herein generally relates to machines for forming alternate or zigzag folds in continuous material, such as business forms or the like. More particularly, the instant invention is directed to new and useful improvements in machines of the type shown in U.S. Pat. No. 3,352,553, issued to David Preston on Nov. 14, 1967.

It is a primary object of the instant invention to provide a machine which is capable of continuous operation in a trouble-free manner, producing at a high speed a uniformly folded product which discharges from the machine in a smooth continuous flow so as to facilitate the subsequent packaging thereof.

In known machines of a generally similar design, various problems have arisen including the tendency for the introduced strip material to wrap around or become entangled with the feed roller and a tendency for the folded material to exit from the machine in bunches, rather than a smooth continuous flow. Difficulties have also been encountered in adjusting the stops so as to accommodate materials of different thicknesses or folds of varying depths.

It is to overcome the above deficiencies that the present invention has been devised. More particularly, the machine herein incorporates a feed roller and hold-down roller arrangement whereby a positive feeding of the strip material into the folding portion of the machine can be effected without any danger of the material wrapping about the feed roller or being improperly fed. In addition, the material handling and folding elements have been so constructed and orientated as to provide for a continuous folding operation wherein there is effected both a smooth positive folding of the strip and a discharge of the finished product without breaks or bunches. Such advantages are achieved through the utilization of special roller guided flat belts on the material moving belt units, stops, and particularly a stop at the discharge end of the machine, which cooperate in producing the folds and providing for a smooth discharge of the folded material, material boosting means associated with each stop with such means consisting of spaced rotating relatively narrow fingers which only periodically engage the material and do not disrupt the smooth flow thereof. Both the stops and material boosting means associated therewith are mounted for positive adjustment through a pinion and rack arrangement.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIG. 1 is a perspective view of the material feeding, folding and discharge portion of the machine, the supply roll not being illustrated;

FIG. 2 is a top plan view of the machine as shown in FIG. 1;

FIG. 3 is an enlarged longitudinal cross-sectional view through the machine;

FIG. 4 is an enlarged cross-sectional detail taken substantially on a plane passing along line 4-4 in FIG. 3;

FIG. 5 is a perspective detail of the stop and material boosting means at the discharge or outlet end of the machine; and

FIG. 6 is a cross-sectional detail similar to the central portion of FIG. 3 illustrating the material boosting means in a rotated position.

Referring now more specifically to the drawings, the machine includes a rigid frame 10 having a front or near side 12 from which the machine is operated, a rear or far side 14 on which the drive train will be mounted, an input end 16, and an output or discharge end 18.

The strip material or paper to be folded will normally be provided in an enlarged roll mounted on a spindle outward of and in alignment with the input end 16 of the machine. The roll spindle in turn will normally be mounted on brackets affixed to and projecting from the frame 10. It is contemplated that an adjustable brake be utilized so as to provide for an even drag on the stock material. The paper itself will be preperforated at regular intervals with it being the function of the machine to form the folds along the perforations.

An elongated feed roller 20 extends transversely across the machine frame 10 and is mounted on a driven shaft 22 journaled in the front and rear sides of the frame 10. This roller 20 is located generally centrally of the frame 10 and receives the introduced strip of material or paper 24 thereover for discharge downwardly between a pair of belt units 26 and 28. The strip of material 24 is frictionally held against the feed roller 20 by a cooperating hold-down roller 30. The hold-down roller 30 has the shaft thereof rotatably journaled on the free ends of a pair of swinging arms 32 pivotally supported by an elongated shaft 34 extending between and supported by the opposed front and rear frame side walls. The hold-down roller 30 is so orientated as to engage the forward face of the feed roller 20 at or just above the point at which the strip of material 24 moves downward away from the roller 20. This specific positioning of the hold-down roller 30 is considered particularly significant in that heretofore the hold-down roller has been positioned so as to engage the feed roller 20 along the top thereof and substantially spaced from the point of discharge of the paper. Thus, there existed a substantial tendency for the material to improperly feed, and in fact sometimes wrap around the feed roller itself, thus causing a complete shutdown of the machine until a clearing of the blockage was effected. In order to vary the frictional grip on the material, a weight 36 is slidably mounted on an outwardly projecting rod 38 engaged with a crossbar 40 fixed between the swinging arms 32. Appropriate setscrew means 42 is utilized to lock the weight 36 in the desired adjusted position.

Each of the belt units 26 and 28 is orientated longitudinally along the frame 10 between the input and output ends 16 and 18 thereof, and includes side plates or panels 44. Each pair of side plates 44 pivotally mounts on an inner drive roller 46, the shaft of which is journaled in the front and rear sides of the frame 10. The plates 44 in turn mount an outer adjustable idler roller 48, spaced endless belts 50 engaging about the rollers 46 and 48. These belts are flat rather than V-belts and thereby enable the utilization of smooth rollers and also allow for a precision weaving of the belt so as to specifically adapt them for paper handling. A belt guide 52 is also mounted on each belt unit 26 and 28 below the upper run of the spaced flat belts 50 and immediately outward of the corresponding drive roller 46. Each of the guides 52 consists of an elongated shaft 54 having

the opposed ends thereof journaled in the opposed side plates 44, and a series of spaced roller sections 56 which receive the belts 50 therebetween so as to maintain the belt spacing.

A pair of mounting blocks 58 are positioned immediately inward of the side panels 44 of each of the belt units 26 and 28, each of these blocks 58 being slidably mounted on an elongated guide rod 60 fixed to the corresponding side panel 44 in inwardly spaced relation thereto. An appropriate setscrew or the like 62 is threaded downwardly through the upper portion of each of the mounting blocks 58 for selective engagement with the guide rod 60 for a locking of the block 58 thereto in any adjusted position. The adjustment of each pair of blocks 58 is synchronized, utilizing an elongated shaft 64 extending transversely across the corresponding unit and through the upper portions of the associated blocks 58. The shaft 64, immediately beyond each of the blocks 58, mounts a pinion 66 thereon which in turn engages with an elongated rack 68 defined along the upper edge of the adjacent side panel 44. The rod or shaft 64, at the front of the machine, projects forwardly and mounts a manually manipulable handle 70 which, upon being rotated, effects a synchronized positive longitudinal adjustment of the mounting blocks 58 without any slippage or necessity for readjustment such as would occur were stretchable chains and sprockets utilized. Once the blocks 58 are positioned where desired, the locking setscrews 62 are engaged with the guide rods 60.

Each pair of blocks 58 mounts abutment means or a stop assembly which extends transversely therebetween. The stop assembly associated with the belt unit 28 toward the input end 16 of the machine is designated by reference numeral 72, while the stop assembly associated with the belt unit 26 toward the output end 18 of the machine is designated by reference numeral 74. Each stop assembly 72 and 74 includes an elongated flat base plate or flange 76 transversely underlying the lower runs of the belts 50 of the associated belt unit and having the opposite ends thereof rigidly affixed to the lower ends of the associated blocks 58. The stop assembly 72 is completed by a series of upwardly directed fingers 78 projecting perpendicularly from the inner edge of the associated base flange 76 at right angles thereto, these fingers 78 projecting upwardly between the associated belts 50 and being spaced so as to accommodate the belts 50 therebetween.

With regard to the abutment means or stop assembly 74 associated with the belt unit 26, fingers 80 are likewise provided on the inner edge of the associated base plate or flange 76. However, these fingers 80, rather than defining a sharp right angular corner with the inner edge of the plate 76, have smooth arcuately curved lower end portions which engage the inner edge of the flange 76 and provide a rounded corner about which the folded stock can flow both evenly and smoothly. The upper portion of each of the fingers 80 is orientated perpendicular to the associated base flange 76 as has been done heretofore. However, it is the curving of the lower portions of the fingers 80 which is considered particularly unique and highly significant as a means for ensuring an effective flow of the folded stock from the machine. Incidentally, it will of course be ap-

preciated that the fingers 80 are also spaced for the accommodation of the associated belts 50.

Positioned immediately inward of each stop assembly, and in parallel spaced relation thereto, is a material positioning or boosting means 82. Each of these means 82 consist of an elongated shaft 84 overlying the lower runs of the associated belts 50 and having the opposite ends thereof journaled in the opposed mounting blocks 58. The shaft 84 is so positioned as to be in contact with the upper surfaces of the lower runs of the belts 50 for a rotational driving of the shaft 84. The actual boosting engagement with the folded paper is effected by means of a series of radially projecting short rod sections or fingers 86 fixed to the shaft 84 in diametrically opposed pairs at spaced points therealong. Each of these thin projecting sections terminates in a flattened outer end which provides for point contact with the paper fold immediately therebeneath just prior to an engagement of the fold against the corresponding stop assembly. Each material boosting means is positioned at a critical point where the folded stock has a tendency to slow down prior to reaching the associated stop assembly. The fingers 86 engage the stock momentarily so as to ensure proper movement of the stock against the stop, the fingers 86 loosing contact with the stock prior to an engagement of the stock with the stop. This is contrary to the folding and boosting means provided on similar machines such as that illustrated in the Preston patent. For example, the boosting or impressing rollers in Preston remain in contact with the several last folded sheets, thus tending to provide a continuing varying pressure on the sheets and producing high and low places whereby the next sheet to be fed thereon can, because of the continuous engagement, be either stopped completely or misfolded. Such problems are avoided in the device detailed herein.

Positioned beneath the belt unit 26, at the output end of the machine, is a table or table-like horizontal panel 88. A series of flat conveyor belts 90 have the upper runs thereof extending over the panel 88 and rearwardly therebeyond about a transverse drive roller 92. The belts 90 also extend about an idler roller (not illustrated), at the output end of the panel 88 whereby a continuous traveling of the belts 90 can be effected for a discharge of the folded material or stock at the output end of the machine. The tabletop or panel 88 can, as will be appreciated from FIG. 3, terminate short of the paper accommodating space between the upper belt sections 26 and 28, with the overlying belts 90 forming a support surface on which the material 24 folds. Alternately, the panel 88 can be extended rearwardly so as to combine with the belts in providing a paper accommodating support surface.

A vertical adjustment of the delivery table belts 90, rearward of the table panel 88, is provided for by means of a transversely elongated roller 94 mounted on an extending between the free ends of a pair of arms 96 pivoted to the opposed portions of the machine frame 10, an upwardly directed adjusting screw 98 engaging upwardly against one of the arms 96 so as to provide the desired upward or downward swung positioning of the roller 94. As will be best appreciated from FIG. 3, this roller 94 is located immediately forward of the back fold forming booster means and stop assembly so

[57] ABSTRACT

Lengths of material, such as plastic bags, fed from a bag forming machine are individually folded one or more times preparatory to packaging. Each length of material is wrapped around spaced and axially opposed vacuum pickup rollers to form a hollow cylindrical roll on said rollers. The roll is then bent in half by means of a blunt edge blade disposed with its longitudinal axis transversely related to the longitudinal axis of said hollow roll and the hollow roll is pushed in between two creasing rollers which bring both halves of the cylindrical roll together and squeeze each half into a flat creased folded portion.
